(57) **CLAIM**

The ornamental design for a tire tread, as shown and described.

DESCRIPTION

FIG. 1 is a perspective view of the tire tread, showing my new design;

FIG. 2 is an enlarged partial front elevation view thereof;

FIG. 3 is a left side elevation view thereof; and,

FIG. 4 is a right side elevation view thereof.

The tire tread pattern is repeated uniformly around the circumference of the tire. The dash-dot lines showing the boundaries of the claim and the broken lines depicting unclaimed subject matter do not form a part of the claim.
